UNITED STATES PATENT OFFICE.

LOUIS COATSWORTH, OF CHICAGO, ILLINOIS.

DESIGN FOR A CASING FOR MOTION-PICTURE APPARATUS.

• 50,145.

Specification for Design.

Patented Jan. 9, 1917.

Application filed November 7, 1916. Serial No. 130,074. Term of patent 3½ years.

To all whom it may concern:

Be it known that I, LOUIS COATSWORTH, a citizen of the United States of America, residing at Chicago, in the county of Cook and State of Illinois, have invented a new, original, and ornamental Design for a Casing for Motion-Picture Apparatus, of which the following is a specification, reference being had

to the accompanying drawing, forming a part thereof, and which represents a perspective view of my new design.

I claim:

The ornamental design for a casing for motion-picture apparatus, as shown.

LOUIS COATSWORTH.
